[57] CLAIM

The ornamental design for a reloader die, as shown and described.

DESCRIPTION

FIG. 1 is a front elevational view of my reloader die showing my new design;

FIG. 2 is a side elevational view thereof, reduced scale, the other sides being identical;

FIG. 3 is a top plan view thereof, reduced scale;

FIG. 4 is a bottom plan view thereof, reduced scale; and,

FIG. 5 is a front elevational view, all other sides being identical thereto, of a second embodiment of my new design.

FIG. 1

FIG. 2

FIG. 3

FIG. 4

FIG. 5
